T. FELLOWS

HOLLOW MASONRY WALL CONSTRUCTION

Filed May 13, 1925

INVENTOR.

THOMAS FELLOWS.

John H. Gatzner Jr.

ATTORNEY.

UNITED STATES PATENT OFFICE.

THOMAS FELLOWS, OF LOS ANGELES, CALIFORNIA.

HOLLOW-MASONRY WALL CONSTRUCTION.

Application filed May 13, 1925. Serial No. 29,979.

To all whom it may concern:

Be it known that I, THOMAS FELLOWS, a citizen of the United States, residing at Los Angeles, county of Los Angeles, and 5 State of California, have invented a certain new and useful Hollow-Masonry Wall Construction, of which the following is a specification.

My invention relates to building construction and it has especial reference to a hollow masonry or brick-wall construction, an object of the invention being to provide a simple means by which front and rear parts of a hollow brick construction may be solidly 15 bound together by headers, which are invisible.

Another object of my invention is to provide a hollow brick wall construction presenting an entire stretcher face with no interruption by transverse headers.

Another object of my invention is to provide a system of hollow wall construction by which metallic and other perishable ties or bonds are wholly eliminated from a hollow 25 brick wall.

Another object of my invention is to provide a unit construction for hollow walls of brick which may be securely bonded together by a novel arrangement of headers of 30 the same or similar material, whereby moisture, heat and cold are retarded or prevented from being transferred from one wall to another, and whereby a strong and substantial hollow wall of brick may be erected.

Another object of the invention is to provide a novel construction of hollow masonry or brick which may serve as a form for concretionary material, and thus enable a brick or masonry wall or structure to be erected 35 simultaneously with the concrete core. By this method a perfect, and solid union between the brick and concrete may be effected as the erection of a building or unit progresses, and wood or other forms may thus be 45 wholly eliminated. These hollow walls may be filled with insulating material or the air space itself may serve the purpose of insulation.

Another object of the invention is to provide a structural building unit which serves to accomplish the purposes expressed herein.

Another object of the invention is to provide a substantial brick construction of light weight, to reduce the cost of brick structures, 50 to reduce the weight upon the foundation

and to replace the solid mass construction hitherto used.

These and other objects are accomplished by the structure illustrated in preferred form in the accompanying drawing, in 60 which,

Fig. 1 is a fragmentary plan view of a hollow wall section, embodying my invention.

Fig. 2 is a perspective detail of a half-width brick or building unit.

Fig. 3 is a perspective detail of an ordinary or simple brick or unit.

Fig. 4 is a front view illustrating the uniform stretcher face.

Fig. 5 is a sectional view of line 5—5, Fig. 4, showing a hollow wall constructed according to my invention.

Fig. 6 is a plan view illustrating a hollow wall built with front and rear walls showing the method of placing the bonding headers and the stretcher half-width brick, and also showing the use of the hollow wall as a form for concrete.

Fig. 7 is a sectional end view on line 7—7 Fig. 6.

Fig. 8 is a perspective view of the structure shown in Fig. 6.

Fig. 9 is a plan view showing front and rear wall with all stretcher faces and the invisible header bond for securing together two walls.

Throughout the several views, like reference numerals denote like parts.

Referring to the drawing in detail, and particularly to Figs. 1, 4 and 5, my invention is shown embodied in a ten-inch structure, composed of two spaced walls 1 and 2, severally built up with brick or other building units 3 and 4, the outside of one of the walls 95 to wit 1, presenting an all stretcher face. The walls 1 and 2 are, as stated, spaced apart, and are bonded together at definite intervals by cross or transverse headers 5 which are provided at such intervals vertically as required by the height of the wall and the number of bonding headers needed. These headers 5, as seen in Fig. 5, are incorporated with the rear wall 2 so that the one end 5' thereof is vertically aligned with the units 4 105 composing such rear wall, and they extend at right angles to such rear wall, and bridging the space A between the walls 1 and 2, project into and are anchored in the front wall 1. The bonding headers 5 being brick 110

- units of ordinary dimensions are too short to span the entire distance from the rear of the rear wall 2 to the face of the front wall 1 and hence extend into the front wall 1, as shown in Fig. 5, but for a distance equal to half or approximately half of the front wall. The spaces left by these headers 5 are therefore supplied by the half width brick units 3 shown in perspective view in Fig. 2.
- 10 These half width brick units 3, occurring wherever are provided headers 5 for bonding the two walls 1 and 2, make possible an all stretcher face front wall, in which the bonding headers are wholly concealed.
- 15 Thereby I accomplish the building first of a substantial hollow brick wall, of light construction, amply and securely bonded, and second, I provide a hollow wall of brick or other units, in which the transfer of moisture, heat and cold may be effectively prevented by merely making the bonding headers 5 waterproof and of heat and cold resisting properties.
- 20 In addition, a wall constructed as explained, with the bonding headers 5, bridging the space between the walls 1 and 2, affords an excellent, convenient support for pipes, conduits and wires, which are securely and safely concealed between such walls.
- 25 Referring to Figs. 6, 7 and 8, I have shown therein a wall construction of greater width than illustrated in Figs. 1 and 5, and hence involving a different arrangement of bond, which, however, is merely an extension of the bonding plan followed in the structure previously shown and referred to, the features otherwise being identical with those alluded to in connection with Figs. 1, 4 and 5.
- 30 The structure shown in those views is a seventeen inch hollow wall and composed of front and rear walls 1 and 2. These walls are arranged to be bonded together by the interlocking of a plurality of building brick units 4 with the front and rear walls 1 and 2, respectively, and with one another, the superposition of the bonding headers and the arrangement of same being such that while effecting a perfect, strong and light bond, spaces are provided for conduits and wires, which are safely concealed within the wall, and are securely held in place and out of contact with one another. In a wall of the width stated, the bond between the front and rear walls 1 and 2, respectively, is made by two units 4^a and 4^b, placed end to end, and conjoined by the usual bonding or cement material between the adjoining ends.
- 35 The bonding units 4^b are securely incorporated with the rear wall 2, as shown in Fig. 6, and the outer ends 4^b of the units 4^b are parallel with the face of the rear wall 2 and alined with it. The complementary bonding units 4^a are incorporated and anchored in the front wall 1, into which they are extended for a distance equal to one half the width of the wall 1. This is owing to the fact that the transverse bonding units 4^a and 4^b are not sufficiently long to reach to the outside of both the front and rear walls 1 and 2. In fact such an extent of the bonding units would not be desirable for the present purposes. The distance not occupied by the header units 4^a are filled by the half width units 3 which in the completed wall structure co-operates to present a complete stretcher face, with the transverse brick bonds entirely concealed.
- 40 Since the points of jointure between the bonding headers 4^a and 4^b occur in the space A between the walls 1 and 2, it is preferable to support these bonding units 4^a and 4^b, and the supports which I prefer to employ, are brick units 6 transversely disposed relative to the front and rear walls respectively. Being of less length than the width of the walls 1 and 2, I prefer to arrange the units in the manner shown in Fig. 7, from which it will be seen that they are alternately united to the rear and front walls of the structure, thereby providing alternate spaces B, for wires, conduits, pipes, and the like, which may thereby be held in separated relation within the wall. The construction illustrated and described in Fig. 6 offers a convenient and excellent method of providing forms for concrete 7, with reinforces 8. The concrete mass may be supplied as the erection of the structure proceeds, and it will be obvious that the front and rear walls 1 and 2 of the hollow structure are thereby securely bonded together in permanent relation. In this manner the facing which in this instance comprises the front and also the rear wall may be bound together in the structure as a solid unit.
- 45 Referring to Fig. 9, which shows my invention embodied in a twelve inch wall, it will be seen that the bonding units 4 for the front and rear walls 1 and 2 respectively, being shorter in length than the width of the wall, occupy but part of the width of and are anchored in the front and rear walls 1 and 2 respectively of the hollow unit wall construction, bridging the space C between the walls.
- 50 The unoccupied space on the respective front and rear walls 1 and 2 is filled or supplied by the half width bricks 3, which in this construction, provide for stretcher brick units on both front and rear walls, a feature desirable for interior wall surfaces where uniform stretcher faces are sought.
- 55 In the construction, as explained herein, it will be understood that any cementitious material may be used to bind the units together.
- 60 What I claim, is:
- 65 1. A hollow unit construction consisting

of spaced walls of brick, and transverse brick headers bonding together the spaced walls, the headers extending wholly through one of said walls and part-way through the other of said walls, and brick units in the space unfilled by said headers, said units co-operating with other units to present an entire stretcher face of brick and wholly concealing the headers.

10 2. A hollow unit construction consisting of spaced walls of brick, and means for tying together said walls, said means comprising transverse brick headers incorporated wholly with the brick units in one of said walls and partly with the brick units of the other of said walls, and brick units in the space in said other wall concealing the headers and co-operating with the other brick units composing the structure to present an uninterrupted stretcher face of brick.

3. A hollow brick wall construction consisting of spaced brick walls and bonds for said walls, comprising transverse headers disposed at intervals and incorporated partly with the units of said walls, and brick stretcher units concealing said headers and co-operating with the brick in said wall to present an uninterrupted, stretcher face of brick.

20 4. A hollow unit construction consisting

of spaced walls of brick and bonds for tying together said walls, comprising transverse brick headers disposed at intervals and incorporated wholly with the units of one wall and partly with the units of the other wall, a plurality of vertically disposed supporting units for said bonding headers, comprising brick units associated with the spaced walls of the construction, said units being of less length than the width of the walls, and alternately bonded to opposite walls to provide suitable spaces, and means co-operating with the units of the wall to conceal the bonding headers and present an entire stretcher face.

5. A hollow brick construction for buildings comprising walls spaced apart, and bonding means for said spaced walls, comprising headers extending through and incorporated in one of said walls and transverse rectangular brick headers extending partly through and incorporated in the other of said walls, supports for said headers between said walls, said supports vertically arranged and alternately bonded to the walls, and half-width stretcher bricks concealing said bonding headers.

In testimony whereof I have set my hand.

THOMAS FELLOWS.
